UNITED STATES PATENT OFFICE.

LEON P. MOORE, OF SMITHVILLE, TEXAS.

SEAT-LOCK FOR WAGONS.

SPECIFICATION forming part of Letters Patent No. 767,589, dated August 16, 1904.

Application filed May 28, 1904. Serial No. 210,231. (No model.)

To all whom it may concern:

Be it known that I, LEON P. MOORE, a citizen of the United States, residing at Smithville, in the county of Bastrop and State of Texas, have 5 invented new and useful Improvements in Seat-Locks for Wagons, of which the following is a specification.

This invention relates to detachably securing seats to the side-boards of the bodies of 10 farm-wagons; and it involves the use of clamps carried by the seat and provided with spring-jaws which are forced to grip the side-board by means of cams or eccentrics preferably slightly flattened on one side at such a point 15 that when in engagement the flattened sides prevent accidental disengagement.

In the accompanying drawings, Figure 1 shows a seat supported upon a wagon-body, the view being toward the inner face of one 20 of the side-boards. Fig. 2 is a section on the line 2 2, Fig. 1, looking toward the right.

In the figures, A represents one of the side-boards of a farm-wagon; B, a seat resting upon springs which are supported by and 25 fixed to horizontal bars D, to each of which, near its ends, are secured clamping-hangers E. Each hanger has a body portion F, with an upwardly-turned hook G at its lower end and a downwardly-turned hook H at its upper end. In the lower hook rests the spring-supporting bar D, which is preferably secured 30 by a bolt I. The downwardly-turned hook rests upon the upper edge of the side-board, which is not thick enough to fill the hook. 35 In the space left by the board is placed a spring-jaw J, fixed to the upper part of the hook and having at its free lower end short inwardly-projecting teeth which do not normally reach the side-board. In the hook 40 branch, beside which the spring-jaw lies, is pivoted a cam or eccentric K, provided with a handle L, by which it may be rotated in a plane transverse to the plane of the spring-jaw.

45 The cam normally rests against the jaw without pressing it inward; but when the cam is properly rotated it forces the jaw toward the opposite side of the hook, compelling it to engage the side-board when the hook is 50 placed over the latter. Preferably the cam

is slightly flattened at such point that when in engagement this flat portion rests against the flat spring-jaw. It follows that the cam cannot rotate in such direction as to loosen the grip without having positive rotating force 55 applied to such an extent as to still further flex the spring-jaw and force it slightly farther into the side-board. Obviously the clamp is not likely to work loose. When the clamp is loosened by proper rotation of the cam, the 60 spring-jaw follows the receding face of the cam and returns to normal position out of contact with the side-board by its own elastic force.

It is to be understood that each end of the 65 seat is supported in the same manner and that at least one hanger at each end of the seat is clamped whenever it is desired to make the seat secure against displacement when the wagon is moving.

70 As shown, the cam is mounted in the outer side of the hook; but that is not indispensable to proper working. It is also shown as mounted by dividing the hook and bending the parts about a pintle M, supporting the 75 cam, which lies between the parts; but other constructions may be adopted.

What I claim is—

1. The combination with a rigid, seat-supporting hanger having a hook adapted to drop 80 over the upper edge of the side-board of a wagon, of a spring-jaw secured to the inner side of one branch of the hook, and a cam revolvably mounted upon the hook and arranged to have its surface approach or recede 85 from the side-board as the cam is rotated.

2. The combination with a seat-supporting hanger adapted to rest upon the upper edge of the side-board of a wagon and having rigid parts projecting downward upon the inner 90 and outer faces of said side-board, of a spring-jaw normally lying on the inner face of one of said parts, and an eccentric or cam arranged to force said spring-jaw toward the opposite part.

3. The combination with a seat-supporting hanger having at its opposite ends oppositely-turned, rigidly-connected hooks, of a normally retracted spring-jaw mounted in one of the hooks, and a hand-operated device mount- 100

ed on the hanger and adapted for at will forcing the spring-jaw toward the opposite side of the hook while the seat is at rest.

4. The combination with a rigid hanger having at one end an upturned hook and at the opposite end an oppositely or downwardly open hook, of a seat-supporting bar fixed in the upturned hook, a toothed spring-jaw secured in the other hook, and a cam provided ¹⁰ with a handle for its convenient rotation and

adapted to force the spring-jaw toward the opposite side of the hook to clamp an intervening side-board.

In testimony whereof I have signed my name to this specification in the presence of two sub- ¹⁵ scribing witnesses.

LEON P. MOORE.
